CLAIM

The ornamental design for a grater teeth, as shown and described.

DESCRIPTION

FIG. 1 is a perspective view of grater teeth showing our new design;

FIG. 2 is a right side elevation view thereof;

FIG. 3 is a left side elevation view thereof;

FIG. 4 is a top plan view thereof;

FIG. 5 is a rear elevation view thereof;

FIG. 6 is a bottom plan view thereof;

FIG. 7 is a front elevation view thereof;

FIG. 8 is as front elevation view thereof; the plurality of grater teeth are shown in broken lines for illustrative purposes only and form no part of the claimed design.

FIG. 9 is a front elevation view thereof; the grater and plurality of the grater teeth are shown in broken lines for illustrative purposes only and form no part of the claimed design; and,

FIG. 10 is a front elevation view thereof the size being smaller than that shown in FIG. 1; the grater and plurality of teeth are shown in broken lines for illustrative purposes only and form no part of the claimed design.

(Continued)

The broken lines shown in the figures depict portions of the grater teeth that form no part of the claimed design.
